CLAIM

The ornamental design of a pelican hook, substantially as shown and described.

DESCRIPTION

FIG. 1 is a side elevational view of a pelican hook embodying my new design;

FIG. 2 is a front elevational view thereof;

FIG. 3 is a rear elevational view thereof;

FIG. 4 is a top plan view thereof;

FIG. 5 is a bottom view thereof; and

FIG. 6 is a perspective view from the side showing the hook in its open position with the plunger shown withdrawn.

The side of the pelican hook not shown is the same as the side shown.
